EXPLOSIVELY SEPARABLE FASTENER

Clarence K. Brown, Bellflower, Calif., assignor to Hi-Shear Corporation, Torrance, Calif., a corporation of California

Filed Aug. 4, 1960, Ser. No. 47,415

1 Claim. (Cl. 85—1)

This invention relates to a fastener which may be explosively separated.

An object of this invention is to provide a fastener that will join structural members, primarily in shear applications, with the full shear strength for the size of the fastener and with the capability of withstanding the tensile loads present in such a joint and the necessary installation torques; yet this fastener to be capable of being separated by a relatively small charge of solid propellant material which may be detonated from a remote point by an electrical signal.

A further object of this invention is to provide an explosive bolt which may be installed in an unarmed condition and which may be armed or disarmed for safety at any time.

Conventional explosive bolts have been made in the past but have always contained an explosive charge buried in a recess within the shank. The structure of the bolt had to be weakened to provide for fracture due to the explosive detonation; however, the bolt structure could not be weakened beyond a point where the useful strength of the bolt would be excessively impaired so a relatively large explosive charge was required to separate the bolt. This excessive explosive energy could do damage to adjacent structures. Moreover, this type of bolt would have to be installed in an armed condition without the capability of being disarmed.

According to this invention a separable bolt is made in two primary sections, one having a threaded end and the other a head end. The threaded end section has a reduced diameter which fits a longitudinal bore in the headed end. A third member is employed to retain the reduced diameter of the threaded section of the bolt within the headed section. The longitudinal bore of the headed end is adapted at the head to receive a conventional explosive squib, the retaining member is of a size and form which will fail in shear upon detonation of the squib.

According to a preferred but optional feature of the invention sealing means may be provided between the threaded section of the head section of the bolt to confine the explosive detonation of the squib and direct its full energy to separating the bolt.

The above and other features of this invention will be fully understood from the following detailed description and the accompanying drawings, of which:

FIG. 1 is a side elevation partially in cross-section of one embodiment of this invention shown assembled in structure with a squib and nut in place;

FIG. 2 is a cross-section of the device of FIG. 1 taken at line 2—2 of FIG. 1;

FIG. 3 is a cross-section taken at line 3—3 of FIG. 1;

FIG. 4 is a side elevation in cross-section of another embodiment of the invention;

FIG. 5 is a cross-section taken at line 5—5 of FIG. 4.

In FIG. 1 there is shown a preferred embodiment of this invention. The fastener is shown with two primary sections, 33 being a threaded member and a head member 16. The threaded member 33 is cylindrical in shape with a thread 32, a shank portion 31, and a reduced cylindrical diameter 30. The head end 23 is of geometric shape to accept a wrench and has a cylindrical shank portion 34. The bore 26 is shown coaxially through head

2

member 16 and is of a size to receive a reduced shank diameter 30 of thread end 33 at the shank end of head member 16. At the head end 23 of head member 16 the bore 26 has a thread 17 to accept a standard squib 18. Such a squib conventionally has an explosive chamber 24 and electrical leads 19 and 22 which may be attached to a source of D.C. current 20 and which squib will be detonated by closing a switch 21. In manufacturing this fastener threaded end 33 is inserted into bore 26 of head member 16 and a transverse hole 35 is drilled through both members to accept a shear pin 29. The fastener in FIG. 1 is shown fastening two sheets of structure 14 and 15, shown in phantom, held by nut 12, also shown in phantom.

As a preferred but optional feature the reduced diameter 30 of thread end 33 may have an undercut 27 of a size to receive an elastomeric O-ring sealing member 28. This sealing member prevents leakage of gaseous products of the explosive charge contained in the squib upon detonation and concentrates the entire force of the explosion on surface 25 of thread end 33 to effect shear failure of pin 29, thus separating the fastener and the joint.

In FIG. 4 there is shown another embodiment of this invention. There are two primary members again, a threaded member 50 and a head member 40. Threaded end 50 is cylindrical in shape with a thread 49 at one end, a cylindrical shank 51 and a reduced cylindrical diameter 47 adjacent to shank 51. The reduced diameter 47 terminates in a tapered surface 44. In the reduced diameter 47 there is an undercut of rectangular section 36. Head member 40 has a smooth cylindrical shank 46 which is preferably the same diameter as the shank 51 of thread member 50. There is an enlarged head 48 of geometrical shape to accept a wrench. A longitudinal coaxial bore 42 extends through head member 40, and at the end remote from the head, is enlarged to the same diameter as the reduced shank 47 of the threaded member 50 and terminates in a tapered face 64 to permit the reduced diameter 47 of threaded member 50 to be completely inserted into the bore of member 40. In the tapered face 64 of this enlarged bore 45 there is a recess 38 which is of a shape and size to accept an elastomeric sealing member 39. The bore reduces in size to produce a passage 52 which extends through the head of head member 40. The bore 42 terminates in a threaded area 41 which is adapted to accept a conventional explosive squib. Retaining member 37 is a split, resilient ring which engages groove 36 in threaded member 50 and groove 53 in head member 40 to retain both parts in assembly. To assemble the device sealing ring 39 must first be inserted into recess 38. The retaining ring 37 must be compressed and inserted into groove 53. Groove 53 should be of sufficient depth to allow expansion of ring 37 as the tapered nose 44 of threaded member 50 is pushed into bore 45 of head member 40, thereby expanding retainer 37 until it snaps into groove 36 of the threaded member 50. After assembly of threaded end 50 to head end 40 a hole 56 may be drilled at the parting line 54 at the shank diameter of the two mating parts and transverse to the center line of the two parts and a pin 55 inserted to prevent relative rotation of threaded end 50 with head end 40 during installation torquing of a nut. A conventional squib 58, with electrical leads 59 and 60, is shown in place in the head end 48 of the stud. This squib may be removed at any time to disarm the stud without affecting the structural integrity of the stud or the structure that is assembled with the stud.

In use the fastener of FIG. 4 would be inserted into structure which comprises two or more sheets or members and installed with a conventional nut. A conven-

tional type of explosive squib 58 would be installed in the head end of the fastener with an explosive charge thereby contained within cavity 52. External electrical leads 59 and 60 would connect to a source of power and upon completing the circuit the explosive would detonate. Confined in close quarters the resultant shock wave would act upon surface 43 of threaded member 50 and react against the body of the squib to cause retaining member 37 to fail in shear, blowing both parts out of the structure longitudinally and thereby separating the structure. Due to this design, the retaining member may be made of a strength that will require a very minimum of explosive to create a reliable separation.

This invention is not to be limited by the embodiments shown in the drawings and described in the description, but only in accordance with the scope of the appended claim.

I claim:

A threaded stud assembly for explosive separation which comprises a first threaded member, said member having a threaded end, a smooth shank portion adjacent the threaded end, a reduced coaxial cylindrical section adjacent said smooth shank portion, said reduced cylindrical section terminating in a tapered face at the end opposite said threaded end, said tapered face truncated to form a flat end to said first threaded member, an external annular groove in said reduced cylindrical section adjacent said tapered face; a second member, said second member having a head end, said head end of geometric shape adapted for wrenching, said second member having a coaxial bore extending through said second member, said bore at the end opposite the head end adapted to accept said reduced cylindrical section of said first member in close engagement, said enlarged bore terminating in a tapered shoulder, said tapered shoulder adapted to

fit closely with said tapered face of said reduced cylindrical section of said first member, an internal annular groove adjacent said tapered shoulder, said internal groove adapted to register with said external groove of said first threaded member when said first and second members are assembled one to the other, said bore adapted at said head end of said second member to receive an explosive squib to form a closed chamber for maximum explosive effect in combination with said flat end of said tapered face of said reduced cylindrical section and said coaxial bore of said second member; a retaining ring, said ring split at one side, said ring adapted to engage said external annular groove of said first threaded member and said internal annular groove of said second member to retain said members in assembly; key means between said first threaded member and said second member to prevent relative rotation; sealing means between said tapered face of said reduced cylindrical section of said first member and said tapered shoulder of said bore of said second member adapted to confine an explosive force within said bore for maximum explosive effect.
